Primary Examiner — Mark A Goodwin(74) *Attorney, Agent, or Firm* — Jason P. Mueller; FisherBroyles, LLP(57) **CLAIM**

The ornamental design for a cordless blaster device, as shown and described.

DESCRIPTION

FIG. 1 is a top perspective view of a cordless blaster device showing our new design;

FIG. 2 is a front view thereof;

FIG. 3 is a back view thereof, taken at a 180-degree rotation from the front view shown in FIG. 2;

FIG. 4 is a side view thereof

FIG. 5 is a side view thereof, taken at a 180-degree rotation from the side view shown in FIG. 4;

FIG. 6 is a top view thereof;

FIG. 7 is a bottom view thereof;

FIG. 8 is a side view thereof, shown with a controller mounted to the top of the device; and,

FIG. 9 is an exploded side view thereof, shown with the removable top cover separated from the body of the device. The dotted lines are for purposes of illustration and do not constitute part of the claimed design.
